[57] CLAIM

The ornamental design for a lubricating pad for fifth wheel, as shown and described.

DESCRIPTION

FIG. 1 is a top plan view of a lubricating pad for fifth wheel showing my new design;

FIG. 2 is a front elevation view thereof in inverted condition;

FIG. 3 is a rear elevation view thereof;

FIG. 4 is a right side elevation view thereof, the left side being a mirror image of that shown;

FIG. 5 is a bottom plan view thereof;

FIG. 6 is a top plan view of a lubricating pad for fifth wheel showing a second embodiment of my new design;

FIG. 7 is a front elevation view of FIG. 6 in inverted condition;

FIG. 8 is a rear elevation view of FIG. 6;

FIG. 9 is a right side elevation view of FIG. 6, the left side being a mirror image of that shown; and

FIG. 10 is a bottom plan view of FIG. 6.
